CLAIM

The ornamental design for a shift lever, as shown and described.

DESCRIPTION

FIG. 1 is a perspective view of a shift lever showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front elevation view thereof, shown without environment; and,

FIG. 9 is a back elevation view thereof, shown without environment.

The broken line disclosure is for illustrative purposes only and forms no part of the claimed design.
